This invention relates to low-pressure mercury vapor discharge lamps, more particularly to fluorescent tubes having relatively high electrical or thermal loading.

Such tubes contain besides mercury a rare gas, generally argon at a low pressure to initiate starting. The light output of such tubes does not depend only on the electrical wattage or loading applied to the lamp but also on the efficiency of excitation of mercury resonance radiation which excites in turn the fluorescent material. This mercury resonance radiation is at a maximum at a certain constant and relatively low mercury vapor pressure of a few microns. With increasing power input into the lamp, however, the temperature and therefore the temperature-dependent mercury vapor pressure increases because of the higher energy conversion in the discharge. The specific emission of resonance radiation decreases, and consequently the luminous flux does not increase proportionally to the applied input. The decrease in specific light output in fluorescent lamps with increased loading, and the resulting lower efficiency made such lamps unacceptable in the past.

More recently the efficiency of highly loaded fluorescent lamps has been increased to the point where they may be operated with double the formerly conventional loading, or even more. This may be obtained, for instance, by multiple grooving of the tubular bulb so that the lamp surface and, thereby, the heat conduction of the tube are increased. A drawback to this arrangement is the greater cost of manufacture of the lamp envelope. Another way of obtaining better light output with higher loading consists in providing cooler zones at the ends of discharge lamps by shielding the ends against the heat of the electrodes and of the discharge. By maintaining the ends at about 40° C., some part of the mercury condenses and the vapor pressure in the discharge is regulated. However this produces unsightly dark spaces at the lamp ends.

This invention discloses a new means of increasing the efficiency of highly loaded low-pressure mercury vapor discharge lamps, more particularly fluorescent lamps wherein the operating voltage amounts to less than $\frac{2}{3}$ of the supply voltage, by utilizing the fact that the vapor pressure above an alloy is lower than above a pure metal. Lamps made according to the present invention are distinguished by the fact that there is provided at least one amalgam at places exposed to temperatures substantially not higher than those of the discharge whereby the optimum of efficiency of the mercury resonance radiation is shifted toward higher lamp temperatures by comparison with lamps without amalgam-forming metals.

Amalgam-forming metals have been used in discharge lamps in the past. In low-pressure discharge lamps the amalgam was, for instance, applied to the electrodes or near the electrodes. In these lamps, the amalgam was strongly heated by the electrodes and produced a higher vapor pressure than the mercury in the discharge at a much lower temperature, so that the mercury vaporized continuously out of the amalgam until it was completely decomposed. When the lamp was extinguished, the amalgam-forming metal localized the mercury on the electrode or near the electrode in order to have again a sufficiently high mercury vapor pressure in the lamp when

2

the lamp was started. The amalgam served in these lamps for additional production or subsequent delivery of mercury and could, consequently, not have the property on which the idea of our invention is based, viz., to reduce the vapor pressure during operation of the lamp by comparison with a lamp filled with pure mercury. Consequently, the optimum of resonance radiation of a low-pressure mercury discharge in such lamps could not be shifted toward higher temperatures.

10 In other cases, too, in which amalgams were provided for the purpose of dosing the mercury in lamps operated with undersaturated mercury vapor and without additional reactance and active resistance, the object of the invention could not be realized because lamps having these features were operated at low current intensities only.

In yet other lamps of the high pressure mercury vapor kind, by the addition of rubidium, cadmium and zinc color improvement has been obtained through co-excitation of the added element. By contrast, in lamps according to 20 the present invention the cadmium is not excited to radiation; in other words, the loading and therefore the vapor pressure are sufficiently low that substantially only the mercury is excited to radiation. High-pressure discharge lamps operate with pressures and temperatures several 25 orders of magnitude higher and, consequently, far outside the range required for the optimum of 2537 Å radiation, so that the conditions in these lamps cannot be compared with those in low-pressure discharge lamps.

In the literature there are to be found only such statements referring to properties of amalgams in liquid condition at higher temperatures. With the present invention the prejudice that amalgams have the required reaction speed at higher temperatures only had to be overcome. It came as a surprise on using the present invention that, 35 by suitable selection and composition of the amalgam, the required reaction speed in respect of change of pressure can be obtained also at temperatures prevailing in low-pressure discharge lamps.

According to the present invention, those metals have 40 proved very suitable which, on the one hand, amalgamate in a good manner with the mercury and, on the other hand, attain a balanced condition after a short time. It is, however, well known that with most of the metals a balanced condition is obtained only very slowly at room 45 temperature. Now, there have been found as suitable for the present invention several metals with which this condition may be obtained in a shorter time. A particularly suitable metal is cadmium with which the balanced condition may be obtained after a few minutes only at room 50 temperature.

Generally speaking one may use metals in which the activity coefficient of the mercury in the amalgam formed therewith is smaller than 1, e.g. thallium, cadmium, indium, gallium etc. because then the quantity of metal 55 to be added to the mercury is not too great. The activity coefficient with which the mole fraction must be multiplied in order to obtain the activity, that is the proportion of the vapor pressure above the mixed phase to the vapor pressure of the pure metal at equal temperature, 60 indicates to the extent that it differs from 1 that the behavior of a solution or of an alloy is not ideal. According to the present invention an atomic proportion, if for instance cadmium is used as the amalgam-forming metal, of effective cadmium to mercury smaller than 5, preferably about 0.5 to 2, has proved suitable.

Of course such an amalgam may also be used in fluorescent lamps of usual wattage which are exposed to high temperature loadings.

The amalgam-forming metal or the amalgam itself is, 70 according to a feature of the invention, provided within the lamp over a large surface or distributed throughout substantially its entire extent. It may lie, for instance

as a fine-grained powder or film, on the luminescent coating, or as a translucent protective layer or in the form of an igniting strip or on an underlayer. As previously mentioned, it is located at predetermined places where it is not exposed to temperatures much higher than those in the discharge. Consequently, it is a feature of the present invention that the amalgam does not die directly near or on the electrodes.

Where the amalgam is to be used in powder form, it is desirable to add in the grinding process a hard, neutral material such as silica SiO_2 because the amalgams are, generally, soft and smear when pulverized. The amalgam may be introduced into the finished lamp. If it is introduced before the lamp is finished, it may be desirable to provide for free mercury beside the amalgam in order to have the desired composition of amalgam after the heating process. There may also be brought into the discharge tube simultaneously several amalgam-forming metals, e.g. cadmium and gold.

Another feature according to the present invention consists in that the amalgam or one of its components is intimately mixed or alloyed with a low melting metal, e.g. gallium, soft solder or the like. The mixture is brought into the finished lamp to a predetermined place and heated; after this heat treatment the amalgam adheres fast to the base layer so that it is, in any case, prevented from coming near the electrodes.

The filling pressure of starting gas in lamps according to the present invention should, suitably, be chosen somewhat lower than in conventional lamps. It may also be advantageous to use instead of argon another rare gas, e.g. neon, either simultaneously or alone as the base gas.

In the accompanying drawing, FIGS. 1 and 2 illustrate by way of examples fluorescent lamps embodying the invention.

The illustrated lamps are designed for operation on a line voltage of 220 volts. The tubular bulb 1 to the inner wall of which the luminescent coating 2 is applied has a diameter of 38 mm. and a length of 1.2 mm., being similar in dimensions to the bulb of an ordinary 40 watt fluorescent lamp. There are used as electrodes 3 the well known oxide pasted coils. In the lamp of FIG. 1, the amalgam-forming metal 4 is, for instance, cadmium which is distributed as a fine-grained powder lying in amalgamated condition on the luminescent coating. The starting gas is a filling of argon at a pressure of 1 mm.

In the lamp of FIG. 2 which is otherwise the same as that of FIG. 1, the amalgam of cadmium is provided as a starting strip or narrow conductive ribbon 5 extending substantially the length of the lamp on its internal surface but stopping short of the electrodes.

Electrical data for lamps similar to the foregoing with mercury alone and with cadmium amalgam in different atomic proportions are given in the following table for inputs of 80 watts and 100 watts:

Input: 80 watts

	Hg	HgCd	HgCd ₂
Operating voltage, volts.....	75.5	84	90
Lamp current, amps.....	1.31	1.26	1.14
Efficiency, lm./w.....	61.3	68	65

Input: 100 watts

	68.5	74.5	84
Operating voltage, volts.....	1.80	1.70	1.53
Efficiency, lm./w.....	57.4	61.1	63.1

It can be seen from the above table that for lamps operated with an input of 100 watts, an atomic proportion of Cd:Hg of 2:1 is preferable from the point of view of efficiency. For lamps operated with an input of 80

watts, a proportion of Cd:Hg of 1:1 is preferable. It can also be seen that the gain in efficiency due to the addition of the amalgamating metal is higher the more the lamp is loaded. Consequently when an amalgam is used, fluorescent lamps may be operated at higher temperatures and such lamps have a higher efficiency than ordinary fluorescent lamps of equal outer dimensions. By the addition of amalgamating metal the pressure of mercury vapor at the higher operating temperatures is reduced to a value which guarantees optimum output of mercury resonance radiation.

The efficiency of lamps according to the present invention is increased 10 to 15% by comparison with generally used 40 watt lamps, so that the gain in light flux is considerable. Thus the field of use of fluorescent lamps, for instance in industry, commerce and street lighting, is considerably extended by highly loaded lamps according to the present invention. The invention may also be used in lamps in which the mercury radiation is utilized directly, that is without excitation of luminescent material, as in germicidal lamps.

A further advantage of lamps according to the present invention consists in that the range of possible temperature shifting is much wider than may be obtained by means of the cooling arrangements known hitherto.

The specific embodiments of the invention which have been described are given by way of illustrative example of the invention whose scope is to be determined by the appended claims.

What we claim as new and desire to secure by Letters Patent of the United States is:

1. A low pressure mercury vapor electric discharge lamp wherein the operating voltage does not exceed two thirds of the supply voltage, comprising an elongated envelope having a pair of electrodes sealed into opposite ends and containing a filling of mercury vapor, and an amalgam of mercury with a metal located at places within said envelope exposed to temperatures not substantially higher than those of the discharge therethrough, the metal of said amalgam being selected to shift upward the optimum temperature for generation of mercury resonance radiation within said lamp, the loading of said lamp being sufficiently low that substantially only the mercury is excited to radiation.
2. A lamp as defined in claim 1 wherein the metal of said amalgam is selected from the group consisting of thallium, cadmium, indium, gallium and alloys thereof.
3. A lamp as defined in claim 1 wherein said amalgam is provided as a fine-grained powder within the lamp.
4. A lamp as defined in claim 1 wherein said amalgam is provided in the form of an igniting strip extending internally through the lamp.
5. A lamp as defined in claim 1 wherein said amalgam is admixed with a hard, neutral material.
6. A lamp as defined in claim 1 wherein said amalgam is admixed with silica.
7. A lamp as defined in claim 1 wherein said amalgam is provided as a fine-grained powder admixed with silica and extending substantially throughout the lamp over a large area.
8. A lamp as defined in claim 1, wherein said amalgam is mixed or alloyed with a low melting metal.
9. A low pressure mercury vapor electric discharge lamp comprising an elongated vitreous envelope having a pair of electrodes sealed into opposite ends and containing a filling of an inert starting gas at a low pressure and mercury vapor at a pressure of a few microns, and an amalgam of mercury with cadmium located at places within said envelope exposed to temperatures not substantially higher than those of the discharge therethrough whereby to shift upward the temperature for optimum mercury vapor pressure corresponding to maximum mercury resonance radiation within said lamp, the loading of said lamp being sufficiently low that substantially only the mercury is excited to radiation.

5

10. A lamp as defined in claim 9 wherein the atomic proportion of cadmium relative to mercury in said amalgam is in the range of 0.5 to 5 relative to 1.
